(57) The ornamental design for a plate having condiment wells, as shown.

U.S. PATENT DOCUMENTS**DESCRIPTION**

292,651 A	1/1884	Hentschke
D30,561 S	4/1899	Schubert
876,808 A	1/1908	Kinert
1,520,402 A	12/1924	Clemans
D70,480 S	6/1926	Kopel
1,644,612 A	10/1927	Roberts
D91,229 S	12/1933	Pyle
2,096,825 A	10/1937	Roman

FIG. 1 is a perspective view of a plate having condiment wells;

FIG. 2 is a top view of a plate having condiment wells;
 FIG. 3 is a bottom view of a plate having condiment wells;
 FIG. 4 is a front-side view of a plate having condiment wells.FIG. 5 is a back-side view of plate having condiment wells;
 FIG. 6 is a right-side view of a plate having condiment wells;
 and,

FIG. 7 is a left-side view of a plate having condiment wells.
